UNITED STATES PATENT OFFICE.

CATHERINE LECLERCQ, OF LIMA, PERU.

AWNING.

SPECIFICATION forming part of Letters Patent No. 517,346, dated March 27, 1894.

Application filed September 26, 1893. Serial No. 486,452. (No model.)

To all whom it may concern:

Be it known that I, CATHERINE LECLERCQ, of Lima, Peru, have invented a new and Improved Awning, of which the following is a full, clear, and exact description.

The object of the invention is to provide a new and improved awning which is simple and durable in construction and arranged to form a very effective shelter against the rays 10 of the sun or against rain.

The invention consists of a head mounted to turn and connected by tapes with the slats, and supporting rods adapted to connect with either side of the outermost slat so as to hold 15 the slats in a ventilating, sheltering position or in a closed position during rainy weather.

The invention also consists of certain parts and details, and combinations of the same, as will be hereinafter described and then pointed 20 out in the claims.

Reference is to be had to the accompanying drawings, forming a part of this specification, in which similar letters of reference indicate corresponding parts in all the figures.

25 Figure 1 is a side elevation of the improvement as applied and showing it arranged as a shelter against rain. Fig. 2 is a similar view of the same arranged for sunshine and ventilating purposes. Fig. 3 is an enlarged 30 sectional plan view of part of the improvement on the line 3-3 of Fig. 6. Fig. 4 is a perspective view of the improvement as applied. Fig. 5 is an enlarged transverse section of the improvement on the line 5-5 of Fig. 6; and 35 Fig. 6 is a sectional front view of the same on the line 6-6 of Fig. 5.

The improved awning is constructed on the principle of Venetian blinds and is adapted to be folded in a box A, fastened over the 40 door or window on which the awning is to be applied.

In the ends of the box A, which is open at the bottom, are secured the bearings B, in which are journaled the trunnions C, attached to 45 the ends of a head D, connected by top and bottom tapes E and E', with the several slats F forming the awning proper. The lowermost slat F' of this series of slats F is provided on opposite sides at the ends thereof, 50 with sets of eyes F² and F³, adapted to be engaged by snap hooks G' formed on the upper ends of supporting rods G pivoted at G² to the

door or window casing, as plainly illustrated in the drawings. When the snap hooks G' engage the eyes F², as illustrated in Figs. 1 and 4, 55 then the several slats F are closely folded so as to overlap one another, to form a shelter against rain, and when the said snap hooks G' are connected with the other set of eyes F³, as illustrated in Fig. 2, then the several slats are 60 arranged parallel to each other, with intervening spaces to form a shelter against the rays of the sun, at the same time permitting the air to circulate through the space between the several slats, as will be readily understood by reference to Fig. 2. It is understood, that as the head D is mounted to turn in the casing A, the several slats will readily adjust themselves according to the direction in which the bottom slat F' is turned to connect the 70 latter with the supporting rods G at either of the sets of eyes F² or F³, for the purposes above described.

In order to conveniently turn the head D so as to cause the slats to assume either of 75 the two positions mentioned and to lock the same in place, I provide the ropes H and H', of which the rope H is attached to the head D at one side, while the other rope H' is connected to the other side as will be plainly 80 seen by reference to Fig. 5. The rope H extends from the head D upwardly and rearwardly to pass over a pulley I journaled in suitable bearings secured to the top of the box A, the rope then extending downward to 85 be fastened on a suitable cleat H² attached to the door or window casing and within convenient reach of the operator standing on the ground; see Fig. 4. The other rope H' extends from the head D upwardly and forwardly to pass over a pulley I' likewise supported from the top of the box A, the downwardly-hanging end of the rope H' being 90 adapted to be fastened to a cleat H³ also secured on the door or window casing and preferably on the opposite side from that on which the cleat H² is located. 95

In order to pull the several slats F and the bottom slat F' into the casing A during the time the awning is not in use, I provide the 100 usual ropes J and J' passing through apertures in the ends of the several slats F, the ends of the ropes being attached to the lowermost slat F' so that when a pull is exerted

on the two ropes J and J', the several slats are drawn up into the casing A in the same manner as Venetian blinds, as is well understood. The ropes J and J' pass over pulleys 5 K, K' and K² to then extend downward from the casing A, to be fastened to a cleat J² attached to the side of the door or window casing alongside one of the other cleats H² or H³; as shown in the drawings, alongside the cleat 10 H³, see Fig. 4.

The operation is as follows: When the awning is folded in the casing A and it is desired to extend the same, say for a shelter from the rays of the sun and for ventilating purposes, 15 then the operator first lowers the several slats by releasing the ropes J and J' from the cleat J², so that the several slats move downward by the slackening of the said ropes. The operator then connects the supporting rods G 20 with the eyes F³ on the bottom slat F' to cause the connected slats to assume an inclined position to form an awning, and at the same time the operator pulls the rope H so as to cause the several slats to stand in a parallel 25 position to each other, as plainly shown in Fig. 2. The rays of the sun cannot now penetrate the slats F and at the same time a sufficient space is left between the slats for ventilating purposes. When it is desired to form 30 a shelter for rain, the operator connects the supporting rods G with the eyes F²; see Figs. 1 and 4, and then pulls the rope H' so as to cause the head D to turn until all the slats F assume the position shown in Fig. 1, that is, 35 the lower end of one slat overlaps the upper end of the next following lower slat, thus permitting the rain water to pass from one slat to another on its downward course, without passing between the slats.

40 It is understood that the several slats F are held in their respective position for any desired length of time by fastening the corresponding rope H or H' in place on the corresponding cleat H² or H³.

45 Having thus fully described my invention, I claim as new and desire to secure by Letters Patent—

1. An awning, comprising a head mounted to turn, sets of tapes connected with opposite 50 sides of the said head, slats connected with the said sets of tapes, and supporting rods adapted to connect with either side of the outermost of the said slats, so as to hold the latter in either a ventilating, sheltering position, or in a closed position during rainy 55

weather, substantially as shown and described.

2. An awning, comprising a head mounted to turn, sets of tapes attached to opposite sides of the said head, slats connected at opposite 60 sides with the said tapes, ropes connected with opposite sides of the said head, so as to turn the latter in its bearings, and supporting rods adapted to connect with either side of the outermost of the said slats, so as to hold the 65 latter in a ventilating, sheltering position or in a closed position during rainy weather, substantially as shown and described.

3. An awning, comprising a head mounted to turn, sets of tapes attached to opposite sides 70 of the said head, slats connected at opposite sides with the said tapes, ropes connected with opposite sides of the said head, so as to turn the latter in its bearings, supporting rods adapted to connect with either side of the 75 outermost of the said slats, so as to hold the latter in a ventilating, sheltering position or in a closed position during rainy weather, and means, substantially as described, for folding or extending the said slats, as set forth. 80

4. An awning, comprising a casing, a head mounted to turn in the ends of the said casing, sets of tapes connected with opposite sides 85 of the said head, a series of slats connected at opposite sides with the said tapes and located suitable distances apart, the lowermost of the said slats being provided on opposite sides with eyes, and supporting rods pivoted on the door or window casing and adapted to be connected by their free ends 90 with either set of eyes on the said lowermost slat, substantially as shown and described.

5. An awning, comprising a casing, a head mounted to turn in the ends of the said casing, sets of tapes connected with opposite sides 95 of the said head, a series of slats connected at opposite sides with the said tapes and located suitable distances apart, the lowermost of the said slats being provided on opposite sides with eyes, supporting rods pivoted on 100 the door or window casing and adapted to be connected by their free ends with either set of eyes on the said lowermost slat, and ropes connected with opposite sides of the said head to turn the latter within the casing, substantially 105 as shown and described.
